(57) **CLAIM**

The ornamental design for a cart as shown and described.

DESCRIPTION

FIG. 1 is a front elevational view of a cart comprising the new design;

FIG. 2 is a left side elevational view of the design of FIG. 1;

FIG. 3 is a right side elevational view of the design of FIG. 1;

FIG. 4 is a top view of the design of FIG. 1;

FIG. 5 is back elevational view of the design of FIG. 1;

FIG. 6 is a front, top perspective view of the design of FIG. 1; and,

FIG. 7 is a bottom view of the design of FIG. 1.

The broken lines shown in the drawings depict portions of

the cart that form no part of the claimed design.
